US0D1099560S

(12) United States Design Patent (10) Patent No.: US D1,099,560 S
(45) Date of Patent: * Oct. 28, 2025

(54) WORK LOUNGE

(71) Applicant: Kimball International, Inc., Jasper, IN
(US)

(72) Inventors: Pamela D. Light, Los Angeles, CA
(US); John C. Duffy, Carpinteria, CA
(US)

(73) Assignee: Kimball International, Inc., Jasper, IN
(US)

() Term: 15 Years

(21) Appl. No.: 29/891,259

(22) Filed: May 3, 2023

(51) LOC (15) Cl. 06-01

(52) U.S. Cl.

USPC D6/334

(58) Field of Classification Search

USPC D6/334, 349, 361, 364, 367, 371, 375,
D6/716, 716.1, 716.4

CPC A47C 7/24; A47C 9/00; A47C 3/16

(57) CLAIM

The ornamental design for a work lounge, as shown and described.

DESCRIPTION

FIG. 1 is a front perspective view of a work lounge according to our new design;

FIG. 2 is a front view thereof;

FIG. 3 is a first side view thereof;

FIG. 4 is a second side view thereof;

FIG. 5 is rear view thereof; and,

FIG. 6 is top view thereof.

Features shown in broken lines form no part of the claimed design.

1 Claim, 6 Drawing Sheets
